HYDRAULIC REMOTE CONTROL SYSTEM

Orville A. Wheelon, Pacific Palisades, Calif., assignor to Douglas Aircraft Company, Incorporated, Santa Monica, Calif.

Application May 16, 1939, Serial No. 273,959

8 Claims. (Cl. 60—54.5)

My invention relates to a system for actuating an element which is remotely located from the controlling means and has particular reference to a remote control system which is hydraulically operated and includes advantages of manually operated systems in addition to advantages peculiar to power operated systems.

Furthermore, my control system is irreversible insofar as movement from the actuated element is concerned and is therefore not influenced by vibration or external loads. Also, a positive position indicating means is afforded for the element being actuated in that the movements of the control and the element correspond as in a manually operated system.

Prior practice in power operated controls has, as a rule, been lacking in simple direct position indicating means, and manually operated closed systems have chiefly obtained irreversibility in the control units by excessive friction or braking means not altogether desirable, especially in the event that it is desired to operate a single element from a plurality of control stations. In such an event it would be common practice to set the braking device on the control last operated in order to obtain irreversibility and prevent the controlled element from being actuated by vibration, etc. However, setting the friction or braking device on one control station would also tend to make operation from other stations either impossible or very difficult. Other manually operated closed systems include hand operable pumps with appropriate selectors and electrical position indicators which tend to depart from simplicity of design and operation.

The principal object of the invention is to provide a hydraulic remote control system which may be operated either manually or by pressure from any one of a plurality of control units, and which is irreversible from the operating unit without impairing ease of operation from any of the control units.

Further objects are: to provide a hydraulic remote control system which affords position indication in a direct relation between the controlled element and the control proper; to provide a hydraulic remote control system wherein pressure variations due to temperature changes may be readily corrected; and to provide a hydraulic remote control system wherein a plurality of control handles may control a single operating unit.

Other and further objects will become apparent as the description proceeds.

Referring now to the drawings:

Figure 1 is a schematic diagram of an embodi-

ment of my control system wherein a single operating unit is adapted to be actuated by a plurality of control units.

Figure 2 is a cross sectional side elevation of the operating unit showing a piston adapted to reciprocate; and

Figure 3 is a cross sectional side elevation of one of the control units showing, in addition to other details, spring loaded poppet valves and a piston to which a control handle is pivotally connected.

Figure 4 is a schematic diagram of another embodiment of my control system wherein the control unit is identical to that of Figure 3, and the operating unit is identical in design but is double the size of the unit of Figure 2; the fluid lines being rearranged with respect to the units.

While the invention pertains particularly to an operating unit and a control unit, I have shown in Figures 1 and 4, complete hydraulic systems for the purpose of more clearly describing the units. After understanding the invention, it will be obvious that numerous embodiments are possible wherein the units may be employed with varying results depending largely upon system arrangements.

In the system of Figure 1, a power supply 4 is utilized to drive a pump 6 having a suction port 8 and a pressure port 10. The pump draws fluid from a reservoir 12 through a line 14 and discharges the fluid under pressure from port 10 into a line 16. From line 16, branch lines 18—20—22 convey the pressure fluid to an operating unit 24 and to identical control units 26—26 respectively. Although two control units have been shown, it is obvious that only one, or more than two may be used as necessary to suit particular installation requirements. Likewise, more than one operating unit may also be included in the system if desired. When using a plurality of control units and a plurality of operating units, the control units are connected together in series while the operating units are connected in parallel.

A pressure tank 28, as disclosed in the co-pending application No. 262,958 of Harold W. Adams and Earl S. Kleinhans is connected into line 16 for the purpose of preventing pressure fluctuations or surges from affecting the smooth operation of the units. Also, a check valve 30 is provided in line 16 just ahead of the control units for retaining fluid in these units and in one side of the operating unit in the event of leakage in the fluid supply portion of the system. This valve also serves to maintain irreversibility

of the system insofar as movement of the control unit from the operating unit is concerned if a force greater than the pressure output of the pump 6 is exerted upon the operating unit in one direction. The function of the check valve in this respect will be discussed later in the specification. A floating piston type double acting check valve 32 is located in line 18 and is designed to retain fluid in the other side of the operating unit 24, which is unprotected by the valve 30, and at the same time allow complete operation of the unit in a closed system in the event of leakage or failure anywhere in the system other than in the units proper or in a line 34 interconnecting the units 26-26 or in a line 36 interconnecting one of the units 26 and the unit 24. Both the design and the operation of the valve 32 will be later described.

A line 38 and a line 40 are provided to return the fluid from the units 26 to the reservoir 12 via a line 42 into which they are connected. Lines 44-46-48-50-52-54-56 interconnect the units 26-26 and may be termed control pressure lines in that they convey pressure fluid only when the control units 26-26 are operated.

Referring now to Figure 2, the operating unit 24 comprises a housing 58 having a cylindrical bore 60 in which reciprocates a piston rod 62 including a piston head 64 on the left end thereof. The head incorporates packings 66 for preventing fluid leakage from one side of said head to the other. The right end 68 of the piston rod extends from the housing 58 and is fluid sealed by a packing 70 held in place by a packing nut 12 threaded into the housing at 14 and equipped with a dust seal 76.

The bore 60 is ported at 78 to permit pressure fluid from line 18 to enter the bore on the right side of the piston head 64. The diameter of the piston rod 62 is sufficiently large to restrict the displacement area of the piston head, upon which the pressure may act, to approximately one-half the displacement area upon which the pressure may act on the left side of the head. Pressure fluid from line 36 enters the bore 60 on the left side of the piston head by way of a port 80.

Although, as previously mentioned, the control system may be utilized to actuate any desired element within reasonable limits, for purposes of description it is here assumed that the element is a throttle of an internal combustion engine. A three-armed bellcrank 82 is pivotally connected at one arm to the piston rod end 68 and at another arm to a throttle lever 84. Since in some installations it is desirable, in event of throttle control failure, to have the throttle remain in or be moved to the open position, a spring 86 may be attached to the third arm of the bellcrank in a manner such that the tension of the spring will move the control to the desired position in such an emergency. This spring is easily overcome by the fluid pressure in the control system under normal operating conditions but is of sufficient strength to move the piston if opposing pressure is absent.

With reference to Figure 3, the control unit 26 comprises a body 88 having a plurality of ports 90-92-94-96-98-100. Port 90 connects the line 36 from the operating unit into a piston chamber 102 in the lower right side of the control unit, and port 92 connects the return line 38 into the left end of a poppet valve chamber 104 in the upper right side of the control unit. Port 94 connects the control pressure line 44 into the right end of the poppet valve chamber 104,

and port 96 connects the control pressure line 46 into the right end of a poppet valve chamber 106 in the upper left side of the control unit. Port 98 connects the supply pressure line 20 into the left end of the poppet valve chamber 106. Port 100 connects the control pressure line 34, extending from the second control unit into a piston chamber 108 in the lower left side of the first mentioned control unit or, if only one unit is installed in the system, the port 100 may be interconnected with the ports 96-94.

A piston 110 is provided with piston heads 112-114 at opposite ends thereof which are adapted to reciprocate in the chambers 102-108 respectively. Each piston head is sealed against fluid leakage by packings 116 and incorporates a spring loaded poppet valve assembly 118, the valve of which is unseated by a stem 120 as the piston moves to the end of its stroke in either direction, the stem coming in contact with and being depressed by the end wall of the piston chamber. The valves are also unseated by pressure fluid depending upon the direction in which the fluid is moving. A fluid passage 122 interconnects the two valve assemblies and allows an interflow of fluid from one piston chamber to the other when both valves are unseated. For example, if the fluid and, consequently, the piston are moving to the right, pressure unseats the valve in piston head 114 allowing fluid to flow through passage 122 until it reaches the valve in piston head 112. This valve checks the flow until the piston has reached the end of its rightward travel and the valve stem 120 is depressed by the end wall of piston chamber 102 whereupon the valve is unseated. Fluid then may flow from port 100 through the passage 122 to port 90 until the left end of the operating unit bore 60 is filled, with the piston 64 moved to the extreme right end of its travel. It may be seen that with the piston chamber 102, the line 36, and the left end of the operating unit piston bore 60 filled with non-compressible fluid, the initial rightward movement of piston 110 will force fluid from the chamber 102 to the operating unit, consequently moving the piston head 64 in a corresponding amount, in which case no fluid will flow through the passage 122 because the system is completely filled between the control unit and operating unit pistons. However, the metering valve and fluid passage arrangement is provided for the purpose of correcting any volume variations resulting from temperature changes in that sufficient fluid will be metered through the control unit piston each time a full stroke is executed 55 to maintain a normal pressure acting on the operating unit piston and automatically synchronize all units.

A control lever 124 for releasing pressure to operate the piston 110 is pivotally connected to the piston at 126 and extends upwardly through an opening 128 in the control unit housing 88. This lever has a cam 130 above the pivotal connection to the piston and in the horizontal plane of the poppet valve chambers 104-106, and the cam is adapted to contact and displace either of two valve stems 132-134 depending upon the direction in which the lever is moved. Each valve stem, as it is displaced, unseats its respective spring loaded ball 136 and permits fluid flow from one side of the valve to the other. For instance, if the lever 124 is moved counterclockwise about its pivotal connection 126, the cam 130 contacts and displaces the stem 134 which in turn unseats its respective ball valve 136. This

allows pressure fluid to flow from the constant pressure line 20, through the port 98, past the ball valve and into the control pressure line 46 via port 96. Assuming now that only one control unit is in the system and the ports 96 and 100 are interconnected, the pressure fluid enters the piston chamber 108 and moves the piston to the right and, as force is being applied to the lever at 138 by the operator, the axis of lever rotation is then shifted from the pivotal connection at 126 to the lever cam 130.

As long as force is applied to the end 138 of the lever, the valve stem 134 remains displaced and the cam 130 moves relative to the stem until the lever comes to the end of its counterclockwise travel as determined by the beveled end 140 of the opening 128. The shifting of the axis of the lever and the movement of the cam relative to the valve stem is brought about by the piston 110 being moved to the right by the released pressure fluid flowing into the piston chamber 108 and this movement is so correlated that the piston will contact the end wall of the chamber 102 and the lever will contact the beveled end 140 of the housing opening simultaneously.

If only a partial movement of the lever is desired, the force of the operator is removed from the lever at the end of such desired movement. This relieves the pressure being exerted by the lever cam on the valve stem 134, whereupon the valve will seat, halting fluid flow and consequently movement of the piston 110, the piston being retained at the point at which it was thus halted.

Conversely, if the lever 124 is moved in a clockwise direction about the pivotal connection 126, the valve stem 132 is displaced unseating its respective valve 136 and allowing fluid flow from the control pressure line 44 through port 94, past the valve and into return line 38 via port 92. As this flow is permitted, pressure is released from the left side of piston 110 and consequently from the left side of the operating unit piston head 64, and the pressure on the right or smaller side of piston head 64 plus the power of the spring 86 will move piston head 64 and piston 110 to the left whereupon the action of the lever cam and the valve stem 132 will be identical to that described for counterclockwise movement, the cam being removed from contact with the valve by the leftward movement of the piston.

When two or more control units are provided in the system as shown in Figure 1, the units are connected in series and the control levers of all units will move simultaneously in the same manner and degree as the one actuated by the operator. For example, if the left unit 26 is being operated by moving the lever 124 in a counterclockwise direction, fluid will be released from pressure line 22 and will enter the piston chamber 108 via the ball valve 136 and lines 54, 56. This fluid will then force the piston 110 to move to the right, displacing the fluid in piston chamber 102 into the line 34 and consequently into the piston chamber 108 of the right control unit 26. The piston 110 of the right unit will thus be moved to the right causing the lever 124 of the right unit to assume the same relative position as the lever 124 of the unit being operated. Conversely, if the lever 124 of left unit 26 is moved in a clockwise direction, pressure of the cam 130 will be relieved from the valve stem 134, permitting the pressure in line 22 to seat the ball valve 136 and thus seal itself from entering line 54. Then, as the lever 124 is moved further clockwise, the cam 130 will contact and depress the valve stem 132, unseating its respective ball valve.

Unseating this latter valve connects the control unit ports 92 and 94, permitting flow of fluid therebetween. As soon as the pressure is relieved in the line 56 and the valve stem 132 is depressed,

5 the pressure in the line 18 acting on the right side of the operating unit piston 62 will force the piston to the left. This forces the fluid on the left side of the piston back into the line 36 which in turn forces the pistons 110 in the control units 10 26 to the left, moving the fluid in line 56 into line 50, through the ball valve and into return line 40, thence back to the reservoir 12. Of course, if only the right hand control unit 26 is in the system, the port 100 will be connected directly into line 48. In this case, when the piston 110 is moved to the left by the pressure acting on the right side of the operating unit piston, the fluid on the left side of piston 110 will be forced into line 44, through the valve and into return line 20 42 to the reservoir.

The single control unit system which has been described may be visualized in Figure 1 by deleting the pressure line 22, the return line 40, and the lines 34 and 48 interconnecting the units 26; then an additional line should be placed to connect the port 100 of the right hand unit 26 directly with the third side of the T which connects lines 46 and 44. When two or more operating units are provided in the system these units are 25 connected in parallel, in which case branch lines from the control unit piston port 90 would connect to the port 80 of each operating unit. Likewise branch lines from the pressure line 18 would connect to the port 78 of each unit.

30 In the event of failure in the pressure system at any location other than between the control unit piston chamber 102 and the left side of the operating unit piston head 64, the units may be operated manually by the control lever 124 through a closed system. As the lever is moved counterclockwise, the fluid is forced from chamber 102 into the operating unit thus moving the piston head 64 to the right end of its travel against the power of the spring 86. Conversely, as the lever is moved clockwise, a suction is created by the piston head 62 which draws fluid from the operating unit, and the spring, in addition to the suction force, moves the piston head 64 to the left end of its travel.

35 The double acting floating piston check valve 50 32 is located in the pressure line 18 near the operating unit and comprises a housing 142 with valve type seats 144 at opposite ends thereof. A piston 146 is movable from one end of the housing to the other depending upon the direction of fluid flow and is adapted to seat at either end thus shutting off the flow of fluid. The length of the housing is such that a full stroke of the operating unit piston is allowed in either direction before the piston 146 of the check valve seats 55 at either end of the housing. This valve is provided to allow full stroke of the operating unit piston during manual operation through a closed system and also to prevent complete fluid leakage under certain conditions in event of damage to the system. For example, if a break should occur in the line 18 on the right hand side of the valve, the only fluid lost would be that between the valve and the right hand side of the operating unit 62 by reason of the fact that the fluid on the left side of the valve would move the piston 146 of the valve to the right, forcing it to seat and retain the pressure in the main pressure supply line 16. On the other hand, if the break should occur in the main pressure supply line 16 or in the portion of the line 18 which con-

ncts the valve 32 to line 16, the valve piston 146 would move to the left and seat, thus preventing leakage at that point. In this way the valve 32 would cooperate with the valve 30 to maintain fluid in and between the units proper for operation through a manual closed system.

The successful operation of the embodiment just described is based upon the difference in displacement areas of the operating unit piston head. As at present preferred, the area on the left side of the piston head is twice the area on the right side. In this way a common pressure value may work against itself because the pressure on the larger displacement side will overcome the pressure on the smaller displacement side while the pressure on the smaller side is still ample to move the piston when the pressure on the larger side is relieved. When the units are being operated manually through a closed system and no constant pressure supply is available the smaller side of the operating unit piston will not be pressure loaded other than by the spring and this is easily overcome by the fluid force applied manually from the control lever.

The irreversibility of my system is obtained through the closed system feature which feature effectively prevents movement of the operating unit piston by vibration or other external forces regardless of whether the system is being operated manually or by pressure, and, while affording irreversibility, the ease of control from any number of control units which may be included in the system is unimpaired. This is due to the fact that it is impossible to displace the control unit valves other than by a back pressure greater than the pressure supply, or by the control lever proper. In the event that a force greater than the pressure supply should be exerted on the operating unit piston to move the piston leftward and cause a back pressure to displace the valve 136 between control unit ports 96-98, the check valve 30 would be closed by the back pressure and prevent any fluid movement, consequently preventing any movement of the operating unit piston. Rightward movement of the piston is prevented by the pressure output of the pump 6 acting on the small displacement side of the piston.

The manual type position indicating feature of my invention is made possible because the stroke of the control unit piston and the stroke of the operating unit piston are substantially equal. In other words the operating unit piston will reach the end of its rightward or leftward travel simultaneously with the termination of a corresponding travel of the control unit piston. The control lever, being pivotally connected to the control unit piston, then naturally indicates the position of both the control unit piston and the operating unit piston and, likewise, the position of the elements being controlled. If the units become unsynchronized, as previously stated, due to temperature changes or fluid leakage, they will be re-synchronized immediately upon completion of a full stroke by the control unit piston in that both valves in the piston 110 will be opened and fluid will be metered through the control unit piston to return the system to normal; the position indicating feature being regained.

In an alternate embodiment, as depicted by Figure 4, my system may be utilized for operating elements requiring more actuating force than is obtainable from the embodiment first described. In this alternate system, the control unit 26 is employed as before and the operating

unit 24 is of identical design but is larger, say double the size of the unit used in Figure 1; the fluid lines being so rearranged that operation of the control unit piston acts directly upon the right or lesser displacement side of the operating unit piston rather than upon the left or larger displacement side. The rearrangement of the fluid lines is necessary in order to obtain efficient operation with the double size unit 24 and also to obtain the indication feature. This may be readily understood because if the double size unit were incorporated in the system of Figure 1, the displacement of the control unit piston would be only half the amount required to displace the operating unit piston through a full stroke. In such case, the control unit piston would reach the end of its travel at the time the operating unit piston had completed only half of its travel. The control unit piston valves 118 would then have to open in order for sufficient fluid to be metered through the piston to complete the travel of the operating unit piston. In other words, there would always be a lag between the operation of the control unit and the operating unit, and correct indication of the position of the operating unit piston would not be had on the control lever 124. To obtain the desired coordination and, consequently, indication between the control unit and the larger operating unit, the rearranged system is utilized wherein the supply pressure line 16 is branched into lines 150-152. Line 150 connects to the port 98 of the upper left control unit valve, and line 152 connects to the port 90 of the control unit piston chamber 102. The control unit piston chamber 108 is connected through port 100, by a line 154, to the operating unit port 78 opening to the lesser displacement side of the piston head 64. The chamber on the left end of piston head 64 is connected through port 80, by a line 156, to the port 96 of the upper left control unit valve, and a line 158, teed into line 156, connects into port 94 of the upper right control unit valve. The return line 42, leading to the reservoir 12, is connected at port 92 to the upper right control unit valve.

Operation of this embodiment is similar in many respects to the embodiment first described.

Pressure fluid, being available at port 98, is released when the control unit lever 124 is moved counterclockwise, depressing the valve stem 134. The fluid then flows through line 156 to the left end of operating unit piston head 64 moving the piston to the right and extending the rod 62. This rightward movement forces fluid from the right end of the operating unit, through line 154, and moves the control unit piston 110 to the right, which in turn forces fluid on the right side of the control unit piston back into the line 16 via the line 152. The action of the lever 124 and the valve stems 120 of the control unit piston is the same as previously described. When the control lever 124 is moved clockwise, the upper right control unit valve is opened permitting fluid to flow from line 156 through line 158 and thence into return line 42 which opens the system and allows pressure fluid from line 152 to enter port 90 and move the control unit piston leftward consequently forcing the operating unit piston leftward, retracting the piston rod.

The additional power of this system is obtained through valving the pressure fluid directly to the greater displacement side of the larger operating unit and through utilizing the displacement of the control unit piston to force pressure fluid to the right side of the operating unit.

Still other methods of increasing the power of

systems using the principle of my units will be obvious to those skilled in the art, after understanding the invention, and while the invention has herein been described in its present preferred embodiments, various changes and modifications may be made therein without departing from the spirit and the scope thereof. It is aimed in the appended claims to cover all such modifications and changes.

I claim:

1. In a hydraulic control unit, a piston chamber, a piston adapted to reciprocate in said chamber, a pair of poppet valves, and a control lever, said lever being pivotally connected to said piston and having a cam situated above said piston and in the horizontal plane of said poppet valves, said cam being adapted to unseat either of said valves, each of said valves having two ports which are interconnected when their respective valve is unseated, and the said piston chamber having a port at each end thereof for fluid to enter and exit therefrom and reciprocate said piston in response to operation of said valves by said control lever, said piston having a passage therethrough, a poppet valve being provided at each end of said passage and adapted to close said passage against fluid flow, each of said valves checking fluid flow in opposite directions, whereby fluid flowing in one side of said piston chamber confronts said piston, moving same and unseating the valve in the confronted end, fluid then entering said piston passage where it is retained until said piston reaches the end of its stroke whereupon the valve in the other end of said piston is unseated by contact with the end of said piston chamber.

2. In a remote control pressure system, a unit adapted to control the flow of fluid pressure therein, a piston in said unit adapted to force fluid through said system, a first valve means in said unit for admitting pressure to one side of said piston to move said piston in one direction, a second valve means co-planar with said first valve means for relieving pressure on said side of said piston to permit said piston to return, an operator actuated single lever carried by said piston for movement therewith, said lever lying in a plane transverse to said valve plane and being adapted to individually open and close either of said valves to control pressure movement of said piston and to move said piston manually in the absence of pressure supply, and additional valve means in said piston for by-passing hydraulic pressure through said piston in the direction of piston movement when said piston reaches the end of its stroke.

3. In a remote control pressure system, a unit adapted to control the flow of fluid pressure therein, said unit including a pair of valves, a control lever, a cam on said lever, said cam being adapted to contact and open either one or the other of said valves in response to movement of said lever, a piston adapted to be moved by pressure when either of said valves is open and to be held stationary at any point in its travel when said valves are closed, a single pivot connecting said lever and said piston, said pivotal connection serving to positively coordinate the movements of said lever and piston, and additional valve means in said piston for by-passing hydraulic pressure through said piston in the direction of piston movement when said piston reaches the end of its stroke.

4. In a remote control pressure system, a unit adapted to control the flow of fluid pressure

therein, said unit including a piston adapted to force fluid through said system, multiple valve means for admitting pressure to move said piston, a single lever pivotally carried by said pis-

5 ton, means integral with said lever for individually contacting and operating said multiple valve means, said single lever rotating about said pivotal axis on said piston until its contact with one of said valve means admits pressure to move said
10 piston whereupon said axis of lever rotation is shifted by said piston movement from said pivotal connection to said operated valve means, and additional valve means in said piston for bypassing hydraulic pressure through said piston in the direction of piston movement when said
15 piston reaches the end of its stroke.

5. In a remote control pressure system, a unit adapted to control the flow of fluid pressure therein, said unit including a housing having a plurality of valve chambers and a plurality of piston chambers, a valve in each of said valve chambers, a piston, a piston head movable in each of said piston chambers and fixed to said piston, a control lever carried by said piston for individually opening said valves to admit pressure to and release pressure from said piston and effect movement thereof and adapted to close said valves whereby said flow of fluid pressure and said piston movement are halted, and additional valve means in said piston for by-passing hydraulic pressure through said piston in the direction of piston movement when said piston reaches the end of its stroke as defined by said piston chambers.

35 6. In a remote control pressure system, a unit
adapted to control the flow of fluid pressure
therein, said unit including a housing having a
plurality of valve chambers and a plurality of
piston chambers, a valve in each of said valve
chambers, a piston, a piston head movable in
each of said piston chambers and fixed to said
piston, a control lever carried by said piston be-
tween said valves for individually opening said
valves to admit pressure to and release pressure
from said piston and effect movement thereof and
adapted to close said valves whereby said flow of
40 fluid pressure and said piston movement are
halted, means connecting said lever and said pis-
ton, said last named means serving to positively
45 coordinate the movements of said lever and said
piston and to effect movement of said piston
manually by said lever in the absence of fluid
pressure, and additional valve means in said pis-
ton for by-passing hydraulic pressure through
50 said piston in the direction of piston movement
when said piston reaches the end of its stroke as
defined by said piston chambers.

60 7. In a hydraulic control unit, a piston chamber, a piston adapted to reciprocate in said chamber, valve means for admitting hydraulic pressure to reciprocate said piston, a lever carried by said piston for operating said valve means and for moving said piston manually in the absence of hydraulic pressure, said lever being directly pivoted to said piston, and additional valve means in said piston for by-passing hydraulic pressure through said piston in the direction of piston movement when said piston reaches the end of its stroke as defined by said piston chamber.

70 8. In a control unit, a pair of valve chambers, a valve in each of said chambers, a pressure-in port on one side of one of said valves, a pressure-out port on the other side of said valve, a return-in port on one side of the other valve, a return-out port on the other side of said last named

valve, an operating stem for each of said valves lying in a common plane and spaced from one another, a valve operating lever disposed therebetween and adapted to displace one or the other of said valves, a reciprocating piston in said unit controlled through operation of said valves, a direct pivotal connection between said valve op-

erating lever and said piston, and an additional valve means in said piston for by-passing pressure through said piston in the direction of piston movement when said piston reaches the end of its stroke.

ORVILLE A. WHEELON.
